NIKOLA TRBOJEVICH, OF DETROIT, MICHIGAN

WORM HOB

Application filed July 21, 1930. Serial No. 469,577.

The invention relates to a worm hob of the tangential feed type and resides in a novel construction of flutes and a novel method of relieving the cutting teeth of the said hob.

5 The principle on which the new hob operates is somewhat similar to the principle exhibited in my prior application for patent "taps", Serial No. 204,951 filed July 4, 1927.

10 The object of this invention is to provide a hob of the specified type which although relieved in all its active cutting edges will not lose either its pitch diameter or the thickness of teeth after repeated sharpenings.

15 Another object is to construct a hob that will ream out or burnish the teeth of the gear to be cut in the same operation in which they are generated.

20 Another object is to provide a hob ground in the thread in which the grinding operation extends only to certain burnishing areas found in this hob and not to the roughing teeth, thereby reducing the cost of grinding. Still another object is to produce in a hob a series of roughing teeth having an increased chip room and a series of finishing teeth having a reduced chip room but an increased strength and rigidity. Another object is to construct a hob having roughing and finishing portions of thread in which 25 the roughing teeth merge into the finishing teeth imperceptibly, that is, without causing the finishing teeth to bite off a chip thicker than a predetermined small dimension, usually less than one thousandth of an inch thick and further to preserve this novel quality of the hob after sharpenings.

30 In the drawings:

Fig. 1 is a side elevation of my improved hob.

35 Fig. 2 is the same elevation diagrammatically represented.

Fig. 3 is a cross section of Fig. 2 in the plane 3—3.

40 Fig. 4 is another section in the plane 4—4.

Fig. 5 is still another section in the plane 5—5.

45 Fig. 6 is a diagram explanatory of the burnishing principle by means of a non-relieved hob tooth.

Fig. 7 is the plane development of the pitch cylinder of the hob shown in Fig. 2.

Fig. 8 is an enlarged and exaggerated detail of Fig. 7.

50 Fig. 9 is a hob tooth in perspective explaining the meaning of the terms normal pressure angle and side clearance.

The new hob (see Figs. 1 and 2) is formed from a steel worm, the threads of which are longitudinally intersected by means of a plurality of flutes 11, thereby forming a plurality of cutting teeth 16. The flutes 11 are of a novel construction in that they consist of two superposed systems of flutes, one of a shorter and one of a longer helical lead thus producing compound flutes which are wider at the roughing end 12 of the hob and narrower at the finishing end 13. The hob is provided with a plurality of irregularly bounded true helicoidal surfaces 14 preferably accurately ground over after hardening, said surfaces being distributed adjacent to the front or cutting faces 15 of the teeth 16 in generally increasing areas as approaching towards the rear or large end 13 of the hob. The presence of these non-relieved helicoidal surfaces is essential to the proper functioning of the new hob and serves two purposes, first the said areas catch and removed the minute particles and surpluses of metal left over by the preceding roughing and finishing teeth, thus producing smooth and accurate tooth surfaces and second, they form the reserve or the life of the hob so that it may withstand a considerable number (about fifteen to twenty-five) resharpenings without losing the size or form. Thus, when this hob is resharpened, the face 15 of the flutes 11 is ground over and the areas 14 will thereby be diminished. When all such areas are eventually ground off the hob will be spent and will no longer produce the exact work for which it was intended; however, as long as the said areas remain in at least one tooth, the hob 55 will cut true to size.

60 The front end of the hob (Fig. 2) is a truncated cone 18 approximately comprising in length one half of the total length of the hob. The compound flutes 11 are denoted with the numeral 19 for the flute of the longer lead 100

forming the rear ends of cutting teeth and with the numeral 15 for the flute of the shorter lead forming the fronts or the cutting faces of the said teeth.

5 Figs. 3 to 5 show in various sections that the hob, taken here as an example, has five flutes of the above described divergent or compound type.

The method of backing off the new hob will 10 now be described. As shown in the pitch plane development, Fig. 7, we first mill the required number of flutes along the helix 19 (the helix of the longer lead) thus cutting out the parallel strips bounded by the helixes 15 and 20. The hob teeth 16 are now backed off using the parallel helix 21 as the beginning of the back off in such a manner that the portions of the teeth lying between helixes 20 and 21 will remain cylindrical or non-relieved while the portions lying outwardly from the said helix 21 will be relieved. The 20 distance b of the helix 21 from the helix 20 is proportional to the distances b' , Fig. 5.

After having the teeth 16, thus, partially completed in that each tooth will now be of a hexagonal contour B B' C C' D D' (Fig. 7), comprising a non-relieved portion B B' E E', in the form of a parallelogram in front of it, and a trapezium E E' D D' in the rear of it, 25 we intersect the entire series of cutting teeth by means of the helical flute 15 of a shorter lead, said flute forming an angle G with the flute 21. The effect of this last operation will be to make each tooth in the hob different 25 from any other tooth; however, all teeth taken together will form an organic series exhibiting gradual variations, which is a matter of importance in this theory.

The introduction of the second helix 15 40 produces two important results; first, all teeth to the left of the point A, which is the intersection of the helices 15 and 21 respectively, are of an ever decreasing thickness C C' as counted from the said point A, while 45 the teeth to the right of the point A are all of a uniform thickness but all possess cylindrical lands H H' of an ever increasing width as counted from the point A. Thus, in one single operation we have produced first, a 50 series of roughing of an ever increasing width so that each tooth will take its proportional share of the work, second, a finishing tooth at the point A and third, a series of burnishing teeth having burnishing surfaces arranged according to ever increasing areas.

Still further, these conditions will not change after resharpening. Let us sharpen the hob along the helix 22 parallel to the helix 15, Fig. 8. The point of intersection 55 A will now travel to the right of the hob in its new location A' but the hob will still have the roughing series, the finishing tooth and the burnishing series, as formerly. By the time the point A reaches, thus, the right end 65 of the hob, the hob will be spent, but not until

then. During that time its cutting radius will remain unchanged and the manufactured worm gears will all be exactly alike.

We shall now explain the cutting action of a non-relieved or burnishing tooth and show that in order that the said tooth may not burn up or be abraded by excessive friction it is necessary that the above mentioned roughing series leading to and connecting with the said burnishing series should do so 75 without forming an interval or a gap. I consider the practical means of doing this as the most valuable part of this invention.

As diagrammatically shown in Fig. 6, the non-relieved tooth 16 is forced to take a chip of a thickness e from the workpiece. Let the contacting area of the tooth be denoted with F and the cutting velocity with v then, the force P with which the tooth has to be pressed against the work to produce the deformation e will be

$$P = bFe^c \quad (1)$$

where b and c are constants, the exponent c being of a higher power than one.

The developed heat per second W will be proportional to the delivered friction work, or

$$W = dPfv \quad (2)$$

where d is another constant and f the coefficient of friction.

I observed that the highly injurious force P will be generated at an amazing rate as soon as the jump e exceeds a certain very small limit, maybe less than one thousandth of an inch. However, for the values of e less than that the tool will pass through the work freely, in very much the same manner as if it were relieved. This action may be explained first by the structure of the Equation 1 and second by the fact that by exceeding a certain force P the oil is suddenly squeezed out from between the moving parts of the hobbing machine thus establishing a rigid metal to metal contact in the said parts. Therefore, it is imperative to keep the force P within bounds and that is most effectively done by reducing the jump e and the area F.

The angle G included by the first helix 21 and the second helix 15, Fig. 8, may be calculated to produce a jump e not to exceed a predetermined limit.

When a hob tooth 16, Fig. 4, is backed off, the lathe tool travels along an Archimedean spiral 23 having a drop h from tooth to tooth. The said tool also moves parallel to the axis of the hob thus producing actually a resultant composed of an Archimedean spiral and a straight line, i. e. a conical helix.

The clearance angle M' at the top of the hob tooth (Fig. 9) may be determined from the equation

$$\tan M' = \frac{h}{m} \quad (3)$$

where m is the shortest distance from flute to flute as indicated in Fig. 7.

Let now K be the normal pressure angle of the hob tooth (Fig. 9) and M be the side clearance angle of the said tooth on pitch line, Figs. 7 and 8. Then it stands that

$$\tan M = \tan M' \tan K \quad (4)$$

The side clearance angle M will usually be 10 from 3 to 4 degrees in a coarse pitch high helix angle hob.

We shall now calculate the distance x , Fig. 8, to determine by how much the roughing tooth will be undersize for a distance EA 15 equal to a distance from tooth to tooth as measured along the helix 15.

$$x = EC \tan M \quad (5)$$

but

$$EC = EA \tan G \quad (6)$$

now, the thickness of the chip e , Fig. 6 will be equal to

$$e = \frac{x}{N} \quad (7)$$

where N is the number of flutes in the hob.

It is seen now that we can control the thickness of the chip e (the maximum which the burnishing tooth will be required to take) by properly selecting the dimensions found in the Equations 3 to 6 inclusive. In particular, the whole procedure hinges mostly upon the selection of the divergence angle G . I have found out in practical work that the angle G should be around 4 to 5 degrees, the angle M' about 6 to 7 degrees, thus giving a burnishing chip e between .0007 and .001 inch thick.

Regarding the manufacture of these hobs it may be noted that by one process the flutes 19 may be milled first, then the hob is backed off and the flutes 15 are milled afterwards, and by another process the flutes 19 and 15 both may be milled first and the hob may be backed off afterwards. The hob is then hardened and the faces 15 together with the cylindrical lands 14 are ground. The grinding of the lands 14 may be done in the same machine in which the worms (of which the hob is a counterpart) are ground, thus insuring a perfect duplication of tooth contours at a low cost.

As shown in Fig. 1 which was traced from a photograph, the cylindrical lands 14 are of a more or less irregular shape showing that even when the hob as first backed off was not quite perfect, which is indicated by the irregularity of the lands, yet such a defect will not impair the ability of the hob to produce good work. In this system a single hob tooth may be of such a form that a part of it will be roughing, another part finishing and still another part burnishing without affecting its correct working.

In calculating the dimensions of such a hob we first determine the lead of the helical flute 15 such that it will be at right angles to the thread helix axis customary in all hobs. The angle G is determined afterwards as was 70 shown in detail and the lead of the auxiliary flute 19 is from that calculated.

The principal advantage of this system is that now both the roughing and finishing teeth in a hob may be backed off in the same 75 and continuous operation, thereby producing a series having no jump or interruption at any intermediate point, whereas formerly the roughing teeth had to be backed off separately by means of two divergent helixes, one for each side of the roughing tooth series. This last procedure invariably placed an undue 80 and mostly unforeseen and incalculable excessive loading upon the first finishing tooth; thus shortening the life of the hob.

What I claim as my invention is:

1. A rotary thread tool comprising a threaded portion interrupted by longitudinal flutes forming cutting teeth in which the flutes are of a converging cross section from the entering toward the finishing end and in which the cutting teeth are relieved beginning from a line intersecting the cutting faces at an acute angle at an intermediate point, thereby reducing the entering teeth in thickness and providing the finishing teeth with series of non-relieved helicoidal flanks adjacent to the cutting edges and progressively increasing in area.

2. A worm hob of the tangential feed type comprising a threaded portion interrupted by a plurality of longitudinal flutes forming cutting teeth in which the teeth from the entering toward the finishing end are all backed off with a uniform relief and in an uninterrupted sequence, said back off beginning from a line intersecting the cutting faces at an acute angle at an intermediate point, thus automatically obtaining a differentiated series of roughing and finishing teeth, each tooth differing from the preceding one either in regards to its thickness at one side of the intermediate point or in regard to the width of the cylindrical lands adjacent to the cutting edge at the other side of the said point.

3. A worm hob of the tangential feed type comprising a threaded portion interrupted by a plurality of helical flutes forming cutting teeth in which the flutes are compounded from two helixes, one of a shorter lead forming the cutting faces and the other of a longer lead forming the rear sides of the cutting teeth and in which the teeth are backed off along a helix substantially parallel to the said second helix of the longer lead.

4. A worm hob having a threaded portion and a plurality of compound flutes, each flute being compounded from two divergent helixes in which one helix forming the cutting faces is substantially perpendicular to

the hob thread and the second helix forming the rear ends of the cutting teeth is diverging from the first helix at an angle and is substantially parallel to the helix at which the hob teeth are backed off.

- 5 5. A worm hob of the tangential feed type comprising a threaded portion interrupted by a plurality of longitudinal flutes forming cutting teeth in which the teeth from 10 the entering toward the finishing end are backed off beginning from a line intersecting the cutting faces at an acute angle at an intermediate point, thus automatically obtaining a differentiated series of roughing 15 and finishing teeth, each tooth differing from the preceding one in regard to its thickness at one side of the intermediate point and in regard to the width of the cylindrical lands adjacent to the cutting edge at the other side 20 of the said point and in which the said lands are corrected in form by a passage of a grinder in a helical path relative to the hob axis, thus obtaining a partly ground hob of the same degree of accuracy as if it were ground 25 all over.

6. A worm hob having a plurality of cutting teeth backed off from a helix disposed at an angle relative to the cutting faces of the said teeth and ground over in a helical 30 path concentric with and equidistant from the hob axis, thus producing a series of corrective cylindrical helical surfaces adjacent to the cutting edges and increasing the cutting accuracy of the hob.

35 In testimony whereof I affix my signature.
